LIQUID FUEL DISPENSING PUMP

Roy Frederick Gray, Maidenhead, England, assignor to
Dresser Europe S.A., Brussels, Belgium

Filed Nov. 1, 1973, Ser. No. 411,859

Claims priority, application Great Britain May 3, 1973

Term of patent 14 years

Int. Cl. D20—02

U.S. Cl. D52—2 A

The figure is a perspective view of a liquid fuel dispensing pump showing my new design; the opposite sides, not shown, are identical thereto.

I claim:

The ornamental design for a liquid fuel dispensing pump, substantially as shown and described.
